FENCE-POST.

1,290,416.

Specification of Letters Patent.

Patented Jan. 7, 1919.

Application filed March 4, 1918. Serial No. 220,335.

To all whom it may concern:

Be it known that I, PINCKNEY V. TUELL, a citizen of the United States, residing at Wood, in the county of Mallette, and State 5 of South Dakota, have invented certain new and useful Improvements in Fence-Posts, of which the following is a specification.

This invention relates to new and useful improvements in fence posts, and more particularly to the type which are constructed with slots for receiving the line wires of the fence.

The object of the invention is to construct a post of this character, the slots of which 15 are so formed that the taut wires when placed therein are automatically locked and exert a twisting instead of a pulling action on the post and the latter is provided with means to resist such twisting and thus prevent bending of the post.

Another object is to construct a post of this character which while it will not bend or break under the tension of the wire, will effectively support the wires and will permit them to be quickly and easily applied 25 without the use of fastening elements and when applied will be securely locked in engagement with the post without danger of their becoming accidentally detached, it being necessary that the wires be slackened before their removal from the slots can be effected.

With the foregoing and other objects in view, which will appear as the description 35 proceeds, the invention resides in the combination and arrangement of parts and in the details of construction hereinafter described and claimed, it being understood that changes in the precise embodiment of the 40 invention herein disclosed may be made within the scope of what is claimed without departing from the spirit of the invention.

In the accompanying drawings:—

Figure 1 represents a front elevation of a 45 post constructed in accordance with this invention with parts broken out and with wires shown applied thereto,

Fig. 2 is a side elevation thereof with the wire shown in section,

Fig. 3 is an enlarged detail side elevation 50 showing the formation of the wire receiving slots,

Fig. 4 is a transverse section taken on the line 4—4 of Fig. 3, and

Fig. 5 is a similar view taken on the line 55 5—5 of Fig. 1.

In the embodiment illustrated, a post 1 is shown constructed of a solid piece of metal and constitutes a flat back 2 having a flange 3 extending at right angles from the front 60 thereof midway between its side edges as is clearly shown in Fig. 1, thereby forming a post substantially T-shaped in cross section as shown in Fig. 4. This post has its lower end sharpened as shown at 4 to facilitate its 65 insertion in the ground and this lower portion is provided with anchors in the form of wings 5 and 6 which extend at right angles from the opposite edges of the back 2. These wings or blades 5 and 6 taper downwardly, 70 their outer edges being here shown curved and their upper ends have pockets 7 formed therein which provide fingers 8 to facilitate the retention of the post in the ground.

The front flange 3 is provided at longitudinally spaced intervals with a plurality of wire receiving slots 9, any desired number of which may be employed, according to the height of the post and the distance apart it is desired to space the line wires 80 W. As shown, four of these slots are provided, although obviously the number may be increased or decreased as above stated.

Each of these slots is exactly alike, and hence one only will be described in detail, 85 and it is formed in substantially L-shape, with its upper wall 10 inclined transversely from side to side of the flange and with its rear wall spaced slightly from the back member 2 and is inclined transversely as shown 90 at 11 in Figs. 3 and 4. The lower end of this slot 9 has its end wall inclined transversely in the same direction as the wall 10 as shown at 12. The mouth or opening 13 of the slot 9 is of a width sufficient to permit the insertion of one of the line wires W and terminates at its inner end in a pocket 14, the lower wall of which is formed by the inclined wall 12, while its outer side 95 wall inclines outwardly and upwardly as well as transversely as shown at 15. It will thus be seen that when the wires W are entered through the mouths 13 of the slots 9, and pass into the pocket 14 thereof, after 100 being tightened, they will be brought into the position shown in dotted lines in Fig. 4, and thus exert a twisting action on the post 1, which action will be resisted by the blades 5 and 6 which are driven into the ground.

After these wires have been tightened and then inserted in the slots 11, all possibility of their becoming detached is prevented, and 110

they can only be disengaged by slackening the wires and lifting them out through the mouths 13 of the slots 9.

It may be stated that to insert a taut wire 5 into these slots, a properly constructed tool is necessary to impart a twist to the wire to angle it and cause it to enter the mouth of the slot and pass downwardly into the pocket thereof.

10 It is to be understood that the flange 3 carried by the back member 2 of the post is to be just wide enough to accommodate the slots 9 for the wires, so as to render the post as light as possible and yet provide 15 sufficient rigidity to resist the strains exerted thereon. The formation of the flange 3 at right angles to the back 2 greatly reinforces the post in the manner of an angle iron and permits the flange and the back 20 to be made of comparatively thin metal. The slots 9 are only large enough to accommodate the wire strands and when barbed wire is used, the barbs will operate as stops to retard the disconnection of the wire 25 should a strand be broken.

The blades 5 and 6 being placed at right angles to each other, when they enter the ground will press against the earth in four directions thereby preventing bending or 30 breaking of the post when pressure is brought to bear on it and which also as above stated will resist the twisting strain exerted by the wires.

35 The slots being spaced at their rear ends from the back plate 2 permit the locking action of the wire as shown in Fig. 4, as a taut wire W when dropped into the pocket 14 in its tendency to straighten will force itself against opposite sides of the beveled 40 face of the rear wall of the slot and securely lock it in operative position. It is of course understood that with a post constructed as above described no staples or other fastening elements are necessary, and consequently no 45 driving or hammering on the post is required. Oftentimes it becomes necessary to move a fence, which when staples are used to secure the strands renders the removal of the wires a difficult and tedious task, while, 50 with a fence in which these posts are used all that is necessary is to slacken the strands and then lift them from the pockets.

55 From the foregoing description, taken in connection with the accompanying drawings, the advantages of the construction and of the method of operation will be readily apparent to those skilled in the art to which

the invention appertains, and while I have described the principle of operation of the invention together with the device which I now consider to be the best embodiment thereof, I desire to have it understood that the device shown is merely illustrative and that such changes may be made as are within the scope of the claimed invention. 60 65

I claim:-

1. A fence post having a longitudinally extending flange with an L-shaped wire receiving slot having one arm arranged transversely of the slot and opening through the 70 side edge of said flange, and its other arm extending downwardly longitudinally of the flange, the walls of said slot being inclined transversely.

2. A fence post having anchors extending 75 laterally therefrom at right angles thereto, and wire receiving slots having walls inclined to exert a twisting action on the post which is resisted by the anchors and angling of the post thereby prevented. 80

3. A fence post having wire receiving slots extending longitudinally and transversely, the transverse portion thereof opening through one side wall of the post, the side walls of said slots being inclined 85 transversely.

4. A fence post comprising a flat body member having a longitudinally disposed flange extending at right angles from one face thereof intermediate its side edges, said 90 flange having wire receiving slots opening through its free edge upwardly and then downwardly, the walls of said slots being inclined transversely the bottom of the downwardly extending portion being also 95 inclined.

5. A fence post comprising a body member having a longitudinally disposed flange extending at right angles from one face thereof, said flange having substantially L-shaped slots with one arm opening through the free edge of the flange and the walls thereof inclined transversely, the other arm of each of said slots extending longitudinally of the flange and tapering toward its 100 lower end, the side walls of this slotted arm being also inclined transversely. 105

In testimony whereof I affix my signature in presence of two witnesses.

PINCKNEY V. TUELL.
